CLAIM

The ornamental design for a rest and health pod, as shown and described.

DESCRIPTION

FIG. 1 is a perspective view of rest and health pod, showing our new design;

FIG. 2 is a front view of the rest and health pod;

FIG. 3 is a rear view of the rest and health pod;

FIG. 4 is a left side view of the rest and health pod;

FIG. 5 is a right side view of the rest and health pod;

FIG. 6 is a top view of the rest and health pod; and,

FIG. 7 is a bottom view of the rest and health pod.

Any shading and cross-hatching are not features of the design but are utilized to illustrate the surface contours of the rest and health pod in the drawings.
